UNITED STATES PATENT OFFICE.

EMIL STENKVIST, OF LUDVIKA, SWEDEN, ASSIGNOR TO ALLMANNA SVENSKA ELEKTRISKA AKTIEBOLAGET, OF VASTERAS, SWEDEN, A CORPORATION OF SWEDEN.

METHOD OF TREATING LIQUID INSULATED TRANSFORMERS.

No Drawing. Application filed June 26, 1926, Serial No. 118,858, and in Sweden July 4, 1925.

In transformers intended to operate with their windings immersed in an insulating and cooling liquid, it is of utmost importance that the insulation is free from moisture to the highest possible degree before the immersion in the liquid. The drying process necessary for this purpose, which preferably should be assisted by vacuum as well as by an appropriate heating, is rather circumstantial and must be performed with care and thoughtfulness by persons skilled in the art, if the result shall be satisfactory.

It is frequently not possible to perform the final filling with the insulating liquid immediately after the drying operation. Particularly in the case of large transformers it may with respect to their handling, transport and erection be found necessary to postpone the filling until a moment just before the taking into use of the transformer, which often may occur several months after the time which is most suitable for the drying operation.

The method employed according to the present invention in completing transformers adapted for liquid insulation consists in filling their receptacle immediately after the drying of the transformer (after which

liquid may have been temporarily filled in during testing or the like) with dry air or other gas under a pressure slightly higher than that of the atmosphere so as to prevent the external, moist air from entering the receptacle. A moisture-absorbing material, for instance chloride of calcium, may preferably be introduced in the receptacle, and the latter may be in communication, through a reduction valve, with a vessel containing highly compressed air for replacing the loss through leakage. The enclosed, dry air is expelled immediately before the introduction of the liquid (oil), and then the transformer is ready for operation without further measures.

I claim as my invention:

Method of treating transformers intended to operate in an insulating liquid in a closed receptacle, consisting in drying the transformer, filling the receptacle containing it with a dry gas under a pressure slightly higher than that of the atmosphere for storing or transport, expelling the gas and introducing liquid after storing or transport.

In testimony whereof I have signed my name to this specification.

EMIL STENKVIST.
